UNITED STATES PATENT OFFICE.

JOSEPH ALBERT BAKER, OF SALT LAKE CITY, UTAH, ASSIGNOR TO RAND COMPANY, INC., OF NORTH TONAWANDA, NEW YORK, A CORPORATION OF NEW YORK.

INDEX DEVICE.

Application filed June 9, 1922. Serial No. 567,048.

To all whom it may concern:

Be it known that I, JOSEPH ALBERT BAKER, a citizen of the United States of America, and resident of Salt Lake City, in the county of Salt Lake and State of Utah, have invented new and useful Improvements in Index Devices, of which the following is a specification.

This invention relates to card index devices of the so-called visible index type wherein a series of overlapping cards are supported in a frame in spaced relation with their margins exposed and consists in the novel features of construction and operation hereinafter described and particularly pointed out in the claims.

In the accompanying drawings which illustrate a preferred embodiment of the invention,—

Fig. 1 is an elevational view showing the invention in use;

Fig. 2 is an elevational view of the improved card holder; and

Fig. 3 is a sectional view of a card holder with a card mounted thereon substantially on the line 3—3 of Fig. 2.

In using index devices of the so-called visible index type considerable delay is caused by the necessity of permitting all the card holders to return to their original positions after a card has been inspected in order that the indicia upon the exposed margins of the overlapping cards may be inspected in finding another desired card.

In order to overcome this defect I have produced an improved card holder which is partly cut away along one edge to render a portion of the card supported thereby visible from the back when the card holders are swung to the position illustrated in the upper part of Fig. 1.

This improved card holder is illustrated in Figs. 2 and 3 and comprises a back A of sheet material to which is attached, as by a fabric hinge B, a strip C of card-board or fiber having ends projecting beyond back A to be sprung into the channels formed by side flanges D of a visible index holder E. To permit the lower margin of a card which is to be mounted upon the card holder to be seen from the back of the holder, I cut away the lower marginal portion of back A in the manner indicated at F (Figs. 1 and 2) to provide a longitudinally extending,

transversely narrow recess in its edge. This cutting away of the margin is only sufficient to expose a line of printed matter upon the card, this printed matter to be a duplicate of the indicia that is upon the lower margin of the opposite side of the card.

To permit the indicia to be visible from both sides of the index holder it is necessary that the card G supported by the holder have its lower edge substantially in line with the uncut lower edge of the card holder. I prefer to use for this purpose a sheath H of transparent material such as celluloid formed by bending a strip of celluloid upon itself with the rear face slightly wider than the other as shown in Fig. 3 and with the outer edge rolled as indicated at h to permit easy insertion of the card between the front face of the sheath and back A of the holder. Sheath H may be made fast to the lower portion of the holder in any desired manner, the means shown in the drawing comprising three staples I, one at each end and one in the center. Means for further locking the card in place may comprise diagonal slots J in back A to receive the corners of the card and an integral tongue K formed by further slotting the back A. When a card is inserted with its lower margin in the pocket formed by the front face of the sheath and back A and its top sprung under tongue K and its ends in slots J, it is securely held against displacement in the proper position.

Fig. 1 illustrates the manner of using the device. As shown, the card with the name E. F. Allen thereon is being inspected, this card having been exposed by turning back the card holder immediately thereabove. In this position the index indicia of every card in the index holder E is now visible to the user of the index device, the cards below the Allen card by the provision of the overlapping arrangement and the cards above by the provision of the cut-away portion of the holders supporting the same. Hence, if the user desires next to locate the card to Alden, C. D., it is unnecessary for him to drop the cards above the Allen card before he is able to find the new card inasmuch as he may turn directly to the desired card.

An important feature of the invention consists in that the back of the celluloid

sheath overlaps the lower margin of the holder A throughout the width of the holder including the cut-away portion. Thus the sheath is held against transverse flexing by virtue of its engagement with the lower margin and still further by its attachment to the holder at the center where a staple I or other fastener is provided as described. Moreover the overlapping relationship of 10 the member A and the front member of the sheath facilitates the insertion of a card into the sheath inasmuch as the card is guided into the sheath when slipped downwardly along the front surface of the part A.

15 By reason of the narrowness of the cut-away portion of back A of the holder the latter is not perceptibly weakened and the sheath H may be firmly secured thereto without likelihood of being torn away from 20 the card holder in any ordinary use of the index device.

I claim:

1. A card holder for card index systems having a sheath of transparent material 25 secured thereto at one edge and folded over the body of the holder to form a pocket, and a card removably mounted on said holder with one margin in said pocket, said holder having a portion of the margin 30 covered by said sheath cut away to provide a recess of less width than one wall of the pocket whereby to permit a portion of the margin of the card to be visible from the back of the holder.

35 2. A card holder for index systems having a sheath of transparent material enclosing one margin of the holder to form a pocket, the back of the sheath extending farther from the edge of the holder than the front 40 of the sheath and being secured to the holder beyond the edge of said front, a portion of said margin enclosed within the sheath being cut away to leave a longitudinal recess less in width than one wall

of the sheath to display the margin of 45 the card from the back of the holder.

3. A card holder for use in index devices of the type having a series of holders swinging into overlapping relationship with their 50 margins exposed, the holder comprising a sheet back having a portion of its exposed margin cut away to form a transversely narrow recess, and a folded transparent sheath fitting over the exposed margin and overlapping the back at the inner edge of 55 said recess, whereby an index card extending along the front of said back into said sheath is visible along its margin from the back of the holder by virtue of said cut-away portion.

4. A card holder for use in index devices of the type having a series of holders swinging into overlapping relationship with their 60 margins exposed, the holder comprising a sheet back having a portion of its exposed margin cut away, and a folded transparent sheath extending along said margin to form 65 a pocket to receive an index card, the back of said sheath overlapping the uncut portion of said sheet back throughout the 70 length of said cut-away portion.

5. A card holder for use in index devices of the type having a series of holders swinging into overlapping relationship with their 75 margins exposed, the holder comprising a sheet back having a portion of its exposed margin cut away, and a folded transparent sheath extending along said margin to form 80 a pocket to receive an index card, the back of said sheath overlapping the uncut portion of said sheet back throughout the length of said cut-away portion, and being secured to the sheet back intermediate the 85 ends of the cut-away portion.

Signed by me at Salt Lake City, Utah, 85 this twenty-ninth day of April, 1922.

JOSEPH ALBERT BAKER.
